UNITED STATES PATENT OFFICE

CLARENCE W. UTZMAN, OF WILMETTE, ILLINOIS

FOUNTAIN-PEN HOLDER

Application filed May 28, 1928. Serial No. 281,017.

This invention relates to improvements in fountain pen holders and more particularly to a desk fountain pen holder.

It is an object of this invention to provide a fountain pen holder which is so constructed that the user may readily convert the fountain pen usually carried on the person into a desk set or pen when desired. Other objects of this invention are to provide a pen holder that is adjustable to any size fountain pen, may be adjusted to support the pen, when in the holder, without the use of joints, hinges, etc., at any angle desired, and to provide the bottom of the holder with a covering which may be used as a blotter and also that will prevent its slipping upon the surface of the desk or upon papers when it is used as a paper weight. It is a still further object to utilize the base as an ink well so that the user of the fountain pen may always have a source of ink to refill the pen, at hand.

With these and other objects in view, reference is made to the accompanying sheet of drawing which illustrates the preferred form of this invention, it being understood that minor detail changes may be made without departing from the scope thereof.

In the drawings:

Figure 1 is a view in side elevation of one form of this invention.

Figure 2 is a top plan view of the base with the holder removed.

Figure 3 is a view in side elevation of another form of this invention.

Figure 4 is a similar view with the fountain pen cap in position in the holder.

Figure 5 is a view in transverse vertical section through the form of base shown in Figures 3 and 4, with the holder broken away.

Figure 6 is a perspective view illustrating the manner in which this improved holder is used.

In carrying out this invention a base 1, of any desired material, size or shape is provided of sufficient weight to support the pen, however, it is preferable to provide a base, such as shown in Figures 3 and 4, which is made of metal as shown in Figure 5, and secure a sheet of blotting paper or similar fabric 2 about the under edges thereof which not only can be

used as a blotter but also acts as a pad upon the bottom of the base to prevent the metal thereof from injuring the surface of the desk as well as a means for preventing the base from slipping about upon the supporting surface whether it is a wooden or glass desk top or when employed as a paper weight.

The particular construction of the engaging and supporting member upon the base lends itself to receive the customary cap of a fountain pen and hold the cap at the desired angle to be convenient for the ready insertion and removal of the pen proper. In accordance with this invention the receiving and supporting member is preferably formed of a continuous piece of flexible resilient wire or strip of resilient metal which is looped or bent back and forth upon itself in the form of a cylinder 3, as shown, with the extremities 4 of the wire forming the adjacent loops of the completed cylinder extending downward thereby and anchored in the base. The tops of each loop may be bent to impart a slight flare to the open end of the cylinder 3 for the ready reception of the pen cap 5 and if desired the curved bottom of the loops may be likewise bent to impart a restricted bottom to the cylinder to engage the end of the pen cap.

The receiving member is readily adjusted to any size pen cap as the diameter of the flexible resilient loops forming the cylinder 3 may be increased or diminished at will, by either pushing the loops apart by the insertion of a finger or by squeezing them together, so that the bodies of the loops will snugly receive and engage the pen cap to hold it and allow the insertion or removal of the pen when used as a desk pen and yet allow the ready removal of the cap when it is desired to attach the same to the pen when it is desired to carry the pen upon the person. If the pen cap is provided with a pocket clip, the clip readily passes between the open ends of one of the loops.

The angle at which the pen is to be supported is easily adjusted as the extensions 4 of the looped support which extend into the base are flexible and when inclined to the desired angle will continue to hold the support at that angle until changed.

This invention also contemplates the combination of this particular resilient looped support with the cork, stopper, or cover 6 of an ink bottle, or similar container, 7, preferably one in which the neck 8 extends at an angle to the body of the bottle, as shown in Figures 1 and 2. In such a construction the extending extremity 4 of the resilient loops are anchored in or at one side of the ink bottle closure, and thereby provide a supply of ink for the pen upon the desk whenever the fountain pen needs refilling.

This device provides the base for an inexpensive fountain pen desk set. It comprises only the desk support for the pen and any fountain pen may be supported at the desired angle in it upon the desk. By this simple construction the user of a fountain pen, usually carried upon the person when away from the desk, may take the pen along and have the convenience of using the pen with which he is familiar, as a desk pen, and may not be put to the expense of purchasing both pen and support when he desires a desk pen. While a fountain pen, when carried upon the person, is most efficient when carried with the cap uppermost which prevents the possible leaking of the ink from the movements of the body, the supporting of the fountain pen upon the desk with the cap and pen point downward keeps the pen moist and the feed grooves thereto filled whereby the ink will flow at once whenever the pen is used.

What I claim is:

35. 1. A desk fountain pen holder including a substantially heavy base and an integral resilient and flexible receiving and supporting member of adjustable diameter to receive and engage caps of commercial fountain pens of different diameters to support the same with the pen point down with a portion of said flexible supporting member fixed to said base, whereby the angle at which the pen is supported may be imparted by the user.
40. 2. A fountain pen holder including a substantially heavy base and a receiving member to support the pen with the point down, said member comprising a flexible and resilient metallic strip looped back and forth upon itself to form a cylindrical clamp to receive and retain the cap of a fountain pen supported above said base by securing an end of said strip therein, whereby the angle at which the pen is supported may be imparted by the user.
45. 3. A desk fountain pen holder including a substantially heavy base and a receiving member to support the pen with the point down comprising a flexible and resilient metallic strip bent to loop back and forth upon itself to form a cylindrical clamp of adjustable diameter to receive and retain the caps of commercial pens of various sizes, having the extremities of the metallic strip

extended below the looped receiving member and both anchored in said base, whereby the angle at which the pen is supported may be imparted by the user.

Signed at Wilmette, Illinois, this 23d day ⁷⁰ of May, 1928.
